US00D772819S

(12) **United States Design Patent** (10) **Patent No.:** **US D772,819 S**
(45) **Date of Patent:** **** Nov. 29, 2016**

(54) **RELAY**

(71) Applicant: **OMRON Corporation**, Kyoto-shi, Kyoto (JP)

(72) Inventors: **Yuji Hirose**, Kyotanabe (JP); **Masayuki Shinohara**, Nagaokakyo (JP); **Yasuhiro Tanoue**, Otsu (JP); **Hiroyuki Miyamoto**, Yasu (JP); **Yoshimasa Osumi**, Kyoto (JP); **Kazuhide Hirota**, Moriyama (JP)

(73) Assignee: **OMRON CORPORATION**, Kyoto (JP)

(**) Term: **14 Years**

(21) Appl. No.: **29/500,874**

(22) Filed: **Aug. 29, 2014**

(30) **Foreign Application Priority Data**

Mar. 4, 2014 (JP) 2014-004613

(51) **LOC (10) Cl.** **13-03**

(52) **U.S. Cl.**

USPC **D13/159**

(57) **CLAIM**

The ornamental design for a relay, as shown and described.

DESCRIPTION

FIG. 1 is a perspective view of a relay;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines depict environmental subject matter only and form no part of the claimed design. The oblique short lines in FIGS. 1 and 6 are intended to illustrate that the surface is translucent.

1 Claim, 3 Drawing Sheets
